RAILWAY DIAMOND AND OTHER CROSSINGS.

1,072,706.

Specification of Letters Patent. Patented Sept. 9, 1913.

Application filed July 1, 1910. Serial No. 569,879.

To all whom it may concern:

Be it known that we, CHARLES ALLAN DICKSON, a subject of His Majesty King George V, Emperor of India, mining engineer, of Kodarma, Bengal, British India, and NOEL LINDSAY BURTON-JONES, also a subject of His Majesty King George V, Emperor of India, mica-miner, of Taraghatty, Bengal, British India, have invented 5 Improvements in Railway Diamond and other Crossings, of which the following is a full, clear, and exact specification.

This invention relates to improvements in diamond and other crossings of the class in 15 which a pivoted length of rail or two parallel rails, is or are arranged to pivot so as to form a continuation of the rail or rails at their point or points of intersection, the pivoted rail or rails being capable of being 20 moved so as to form a continuation of either track at the point or points of intersection; and more particularly to automatic devices which when depressed by the flanges of the leading wheels of a vehicle move the rail 25 or rails over, and consists in improvements whereby the number of moving parts is greatly reduced and the work of fitting up is considerably lessened.

In order that our invention may be readily understood reference will be made to the accompanying drawings in which a convenient form of our invention may take is shown by way of example.

In these drawings:—Figure 1 is a plan 35 of the central section of a diamond crossing with automatic actuating and locking mechanism. Fig. 2 is an enlarged side elevation of one of the cranks 16 and connections of rocker rail 8. Fig. 3 is a plan of same.

40 Referring now to Fig. 1, the central portion of a diamond crossing consists of a turn-table of two rails 1 and 2 which are parallel and suitably connected together such as by bars or the like 3 at each end and 45 a central portion 4, such rails 1 and 2 and their connections being pivoted on a pin or trunnion 5 and being capable of movement so that the rails 1 and 2 may be arranged to form a continuation of the track 6 or 50 of the track 7. In the position shown in the drawing they form a continuation of the track 7. Running parallel with the rails and on the inside so as to be depressed by the flanges of the wheels are rails or angle

55 irons 8, 9, 10 and 11. Each of these rails is placed alongside the inner portion of the rail at an inclined angle being pivoted at their lower ends which are farther from the center of the crossing; the bars 8 and 9 being shown pivoted at 12 and 13 respectively. 60 The upper end, the top of which when not set for the particular track is flush with the top of the rail, has a slot 14 therein (Fig. 2) in which a pin 15 on the cranks 16 works. The cranks 16 are pivoted at 17 to the chairs 65 (not shown) and the pins 15 work in slots 18 in the ends of the connecting rods 19, 20, 21 and 22 (Fig. 1); the other ends of which are pivoted at 23 and 24 to the portion 4. The cranks 16 are all inclined from the vertical inward toward the turn-table. When, therefore, the flange of a wheel comes in contact with one of the angle irons 8, 9, 10 or 11 it will press it down and its crank 16 will move forward owing to the crank being set at an angle and when fully depressed 70 will be in the position shown by dotted lines in Fig. 2, the pin 15 moving in the slots 14 as shown. The movement of the crank is conveyed by the connecting rod 19, 20, 21 75 or 22 to the turn-table which moves over so that the rails 1 and 2 are set for the right track. The inner ends of the angle irons 8 and 11 will be in the depressed position 80 when the turn-table is set for track 7 and 85 the angle irons 9 and 10 will be in their normal or raised position flush with the top of the rails, and the parts will remain in this position until the track 6 is required 90 when the flange of the leading wheel comes onto the angle iron 9 or 10 and depresses it causing the turn-table to shift over and both 9 and 10 to be depressed and the angle irons 8 and 11 to rise flush with the rails.

Although in the foregoing description we 95 have described a central diamond section (Fig. 1) as having the rails 1 and 2 pivoted on a common central pivot, it will be obvious that each rail may oscillate on its own pivot, suitable connections being provided 100 for the purpose; and that changes, variations and modifications may be made without departing from the general spirit of the invention. Suitable stops 41 have been provided to limit the movement of the pivoted 105 rail or rails.

Having now particularly described and ascertained the nature of our said invention

and in what manner the same is to be performed, we declare that what we claim is:-

1. A railway switch, comprising rails of a main track and siding rails, a central portion pivoted to swing in a horizontal plane, rails upon such portion and adapted to be brought into alinement with said rails, rails arranged vertically movable adjacent a rail of each track to be engaged by a wheel of a vehicle traveling over the same, horizontally movable actuating rods pivotally connected to the central portion at one end and formed each with a vertical slot at the other end, cranks pivoted at fixed points adjacent to said vertically movable rails and movably connected to the same, and studs connected to said movable rails and cranks and vertically movable in the slots of the actuating rods.
2. A railway switch, comprising rails of a main track and siding rails, a central portion pivoted to swing in a horizontal plane,

rails upon such portion and adapted to be brought into alinement with said rails, rails arranged vertically movable adjacent a rail of each track to be engaged by a wheel of a vehicle traveling over the same and formed with horizontal slots, horizontally movable actuating rods pivotally connected to the central portion at one end and formed each with a vertical slot at the other end, cranks pivoted at fixed points adjacent to said vertically movable rails, and studs in the movable ends of said cranks and slidable in the horizontal slots of the movable rails and the vertical slots of the actuating rods.

In witness whereof we have hereunto set our hands in the presence of two witnesses.

CHARLES ALLAN DICKSON.

NOEL LINDSAY BURTON-JONES.
